(57) **CLAIM**

The ornamental design for a vehicle steering wheel table, as shown.

DESCRIPTION

FIG. 1 is a perspective view of a vehicle steering wheel table showing my new design;

FIG. 2 is a front view.

FIG. 3 is a left side view in conjunction with a motional view of the left side, the broken lines indicating the folding position of the table;

FIG. 4 is a top plan view.

FIG. 5 is a rear view.

FIG. 6 is a bottom plan view; and,

FIG. 7 is a perspective view of the table in fold-up position.
